UNITED STATES PATENT OFFICE.

WARREN E. GLASPEY, OF BRIDGETON, NEW JERSEY, ASSIGNOR TO SPRING STOPPER COMPANY, OF NEW YORK, N. Y., A CORPORATION OF DELAWARE.

MACHINE FOR MAKING BOTTLES, ETC.

Application filed August 2, 1924. Serial No. 729,738.

To all whom it may concern:

Be it known that I, WARREN E. GLASPEY, a citizen of the United States, residing at Bridgeton, in the county of Cumberland and State of New Jersey, have invented a new and useful Improvement in Machines for Making Bottles, Etc., of which the following is a specification.

This invention relates particularly to machines for making bottles, or similar containers, which are provided within the mouth-portion with an internal screw thread; and the primary object is to provide improved means for actuating the mandrels in a machine of this character.

The invention is illustrated in its preferred embodiment in the accompanying drawings, in which—

Figure 1 represents a broken plan view of a bottle-making machine embodying the invention; Fig. 2, a broken, elevational view of the same; Fig. 3, a broken, vertical sectional view illustrating particularly the means for elevating the mandrels, the view being taken approximately as indicated at line 3—3 of Fig. 1; Fig. 4, a plan section on an enlarged scale taken as indicated at line 4—4 of Fig. 3, and illustrating a clutch device employed; Fig. 5, a plan section on an enlarged scale taken as indicated at line 5—5 of Fig. 3, and illustrating a coupling, or connection, between the clutch-head and its actuating shaft; Fig. 6, a broken, elevational view, partly in section, the view being taken at the glass-charging station, approximately as indicated at line 6—6 of Fig. 1; Fig. 7, a broken, vertical sectional view, taken at the blowing station, approximately as indicated at the line 7—7 of Fig. 1 and Fig. 8 is a plan view, partly in section, taken on the line 8—8 of Fig. 7.

It may be stated preliminarily that a bottle-making machine of the general type illustrated is known, such machine involving the use of a rotary mold carrier having an inverted mold mounted on the carrier. Each mold has associated with it a mandrel provided with a thread-equipped tip, the shank of the mandrel being threaded and working through a nut carried with the

mold. In accordance with the present invention, the lower end of each mandrel-shank is equipped with a pinion, or collar, which has its lower side provided with clutch-lugs; and continuously operating local gear mechanism is employed for raising and lowering the mandrels, such gear mechanism comprising a pair of clutch-members disposed beneath the path of the mandrels, one clutch-member being located at the mandrel-elevating station, and the other clutch-member being located at the blowing station. These clutch-members rotate in opposite directions, and each is provided with clutch-lugs for engaging the clutch-lug with which the mandrels are provided, when the mandrels are brought, in turn, in position above the clutch-members.

In the preferred construction which is illustrated in the drawings, A represents the base portion of a frame from which arises a stationary center column A'; B, a rotary mold-carrier having revolvably or invertably mounted thereon a series of mold supports B', upon which are mounted the molds B² B³, a large gear through the medium of which the mold-carrier B is rotated, so that the molds will be carried in an annular path, or orbit; C and C', stationary cams, which serve to close and open the mold; D, a stationary beveled gear segment which serves to rotate the mold supports and invert and then right the molds as they are carried through their orbit; E, a threaded tubular mandrel associated with each mold, each mandrel being equipped at its lower projecting end with a pinion, or clutch-member E', such clutch-member being provided at its lower side with clutch-lugs, as will be explained later; F, local gear mechanism comprising vertical clutch-members F' and F² which rotate in opposite directions and which are adapted, respectively, to raise and lower the mandrels; and G, an auxiliary actuating device located at the intermediate station, that is, at the glass-charging station.

The frame which comprises the base A and column A' may be of any suitable construction. The thick center column A'

serves as an axis about which the mold table B, actuated by the gear B³, turns; and the column A' serves also to support certain mechanisms, including the blow-head which 5 is employed for blowing the glass down into the mold after the charging operation, so that the glass will form properly about the tip of the mandrel in the neck portion of the mold, and including, also, the "blow-back" 10 which is lowered onto the upper end of the mold at the glass-blowing station. The blow-head employed for forcing the glass down into the lower portion of the mold at the glass-charging station is designated H 15 (Fig. 6), and is of the usual construction. The "blow back" head I employed at the glass-blowing station (Fig. 2) is also of well-known construction. It is lowered onto the mold previous to the bubble blowing 20 operation.

The mold table is given an intermittent, or step by step, movement in any desired manner. The mold carrying means comprises a table B, and the series of mold supports B' arranged thereon. Each mold support B' is provided with a hollow trunnion, or gudgeon, 1, and a disk, or face plate, 1^a formed integrally therewith. The hollow trunnion 1 is journalled in a divided bearing box 2, which is securely fastened to the 25 table B.

Each mold B² comprises a pair of main mold sections 3, and a pair of ring mold sections 3^a. These sections meet in a vertical plane and are carried by arms 3^b and 3^a, respectively, whose inner ends are mounted on a pivot 4 carried by lugs 4^a which project from the face plate 1^a. Thus, the mold sections are capable of separating at a plane 30 containing the axis of the mold.

The threaded mandrel E, associated with each mold, works in a nut 5 which is rigidly secured to a bracket 5^a projecting from the lower portion of the face plate 1^a. The 45 bracket 5^a has a tubular portion 5^b in which the nut 5 is rigidly secured, and the upper end of said tubular portion is equipped with a flange 5^c which interlocks with an internal groove with which the ring sections are provided.

In the operation of the machine, the mandrels are elevated, in turn, by the rotating head or clutch-member, F' which turns in a direction to cause the mandrel to be screwed 55 upwardly. The clutch-member F' is driven by a shaft, which, in turn, is frictionally driven by a continuously rotating gear, the arrangement being such that the shaft will stop rotating when the mandrel reaches the 60 upper limit of its movement, while the gear will continue to rotate.

For convenience of reference, the stations shown in the drawing are designated S¹, S², and S³. The mandrels are elevated at the 65 station designated S¹, the glass-charging

operation and the operation of blowing the glass down into the lower portion of the mold is performed at the station designated S², and the complete withdrawal of the mandrels is effected by the head F² at the 70 station designated S³. The reverse, or unscrewing, movement of the mandrels is started, however, by the device G, during the passage of the mold from station S² to station S³. 75

The mold sections are opened and closed through the medium of a plunger 6 which extends through the hollow trunnion 1 of the mold support, the outer end of the plunger being connected, by links 6^a, with the mold sections. Each plunger 6 is equipped at its rear or inner end with a cam roller 6^b; and the movements of the plunger 6 are controlled by the cams C and C'. 80

On the hollow trunnion of each mold support is secured a bevel gear 7. These bevel gears are adapted to travel on the bevel rack D and revolve the mold supports on their axes during the rotation of the mold table B. 85

The molds may be maintained in their normal upright position by any suitable expedient, such as latching devices 8 of which one is shown in Fig. 2. Such a device forms no part of the present invention. It may be added, however, that the device 90 comprises a spring projected plunger 9 adapted to engage the periphery of the face plate 1^a. 95

Each mandrel E preferably comprises a 100 tubular shank portion 10 and a tip portion 10^a, which is provided with a thread adapted to form a thread in the mouth of the bottle. Such thread corresponds in pitch with the pitch of the thread 10^b between the shank 10 and the nut 5. The tip portion 10^a is provided with a tubular shank 10^c and a collar 10^d. Air may pass through the tubular shanks 10 and 10^c and out through radial openings 10^e, thus gaining access to the 105 chamber 11 above the nut 5. The chamber 11 communicates through a central passage 11^a with the neck portion of the mold cavity. Thus, when the mandrel is retracted, air may pass from the bubble blower into the 110 cavity in the glass and blow the glass to complete parison form. 115

The local gear mechanism F, which includes the mandrel elevating head, or clutch, F' and mandrel lowering head, or clutch, F² 120 will now be more fully described. Each of said heads is located directly under the annular path of the pinions, or clutch-members E' carried by the mandrels; and each of the clutch-members F' and F² is so mounted on the upper end of a vertical shaft 12 as to permit a certain amount of "swing" to enable the clutch-member to aline 125 itself properly with the mandrel. Each shaft 12 is splined in a frictionally-driven 130

sleeve 13 mounted in a gear 14. The gears 14 are driven, directly or indirectly, by gears 15 mounted on shafts 16 driven by a connecting shaft 17 actuated by an electric motor 18. The shafts and gears mentioned are supported by brackets 19 mounted on the base of the frame. At the station S¹, (Figs. 1 and 3) the drive from the gear 15 to the gear 14 is direct; and at the station S², (Figs. 1 and 7) an idler 20 is interposed to obtain the reverse rotation.

In each case, the gear 14 is provided with an internal flange 14^a embraced by friction washers 13^a confined between a flange 13^b on the upper end of the sleeve and a disk 13^c, backed by a spring 13^d, whose lower end is confined by lock nuts 13^e with which the lower end of the sleeve is equipped. Thus, the tension of the spring may be adjusted to give the desired friction.

The upper end of each shaft 12 is equipped with a flange, or head, 21 which is confined in a recess in the lower end of the clutch-member F' and F², as the case may be, by means of a nut 22. The head 21 is provided with lugs 21^a which engage corresponding indents, or recesses, with which the clutch-member is provided. The upper surface of the flange, or head, 21 is rounded, or part spherical, and engages a corresponding concave surface, the arrangement being such that the clutch-member F² can rock slightly on the shaft 12, if necessary.

The clutch-member F' is provided with a bore which receives a spring projected plunger 23 which is adapted to enter the lower end of the mandrel, and which tends to act as a centering pin. The clutch-member F² is provided with a similar centering pin 24, having a bore which communicates through an orifice 24^a with a hollow mandrel, as shown in Fig. 7, so that air can be admitted at the bubble blowing station.

Each disc, or pinion, E' is provided at its lower side with clutch-lugs 25 which contact with clutch-lugs 26 with which the clutch-members F' and F² are equipped at their upper ends. One of the lugs 25 is provided with an extension 25^a adapted to serve as a stop, this extension serving to engage a stop 27 mounted on the bracket and serving to limit the downward movement of the mandrel. The upward movement of the mandrel is limited by the mandrel seating itself when it is in the elevated position, in which position the upper surface of the collar 10^d engages a corresponding shoulder with which the neck ring is provided.

The clutch-member, or head, F' is elevated by a pneumatic device J (Fig. 3). This comprises a cylinder 28 in which is mounted a piston 29 carrying a stem 30, whose upper end is equipped with a bearing

head 31 confined in a bearing 32, which is secured to the lower end of the shaft 12. An anti-friction bearing is preferably employed at this point, as illustrated. The arrangement is such that the shaft 12 may rotate freely, while the shaft, or stem, 30 may remain stationary.

Referring to Fig. 7, J' represents a pneumatic device for elevating the shaft 12. The device is similar to the device J. In this case, however, the piston stem, designated 30^a, is provided with a passage 30^b which communicates with an air pressure pipe 30^c. The passage 30^b communicates with a passage 33 extending through the shaft 12, thus enabling air to be admitted to blow the glass to parison form as will be understood from Fig. 7. A coupling 34, similar to that employed at the station S¹ connects the stem 30^a with the lower end of the shaft 12 and permits free rotation of the shaft with relation to the stem. It will be noted that the centering pin 24 serves as a tip which makes air tight connection with the lower end of the mandrel, while the passage through the tip admits the air to the mandrel.

In Fig. 6, a shear designated K is shown. Such a shear may be of any suitable construction and operated in any suitable manner.

It will be noted that the mandrels are rotated by the clutch during elevation, without the use of the teeth on the pinions E'. The lowering of the mandrels may be effected through the clutch-device alone, if desired. However, the auxiliary device G may be employed for "starting" the mandrel downwardly after the glass has cooled somewhat. The device G comprises a curved, or segmental, rack 35 mounted on spring held bell-cranks 36. The rack may, if desired, be of the construction illustrated in my Patent No. 1,453,759, granted May 1, 1923, and may have one or several teeth for turning the mandrel sufficiently to loosen it from the glass.

When the mandrel is being lowered by the unscrewing operation, the force transmitted downwardly is sufficient to overcome the upward pressure of the air on the piston 29, shown in Fig. 7.

In the improved mechanism for raising and lowering the mandrels, the clutch-members mounted on the vertical shafts are capable of a certain amount of self-adjustment to compensate for any slight inaccuracy in the centering of the mold above the clutch-member. The construction is such that the mechanism cannot be injured in operation, and the mechanism will have a long life.

The foregoing detailed description has been given for clearness of understanding

only, and no unnecessary limitations should be understood therefrom, but the appended claims should be construed as broadly as permissible, in view of the prior art.

5. What I regard as new, and desire to secure by Letters Patent, is:

1. In a machine of the character set forth, the combination of a mold-carrier adapted to carry molds in an orbital path, a series of 10 molds mounted on said carrier, a nut mounted below and in alinement with each mold, a mandrel for each mold provided with a thread-equipped tip adapted to extend into the mold cavity and having a threaded 15 shank engaging the corresponding nut and having also a clutch-member at its lower end, a vertical shaft disposed beneath the path of the mandrel and equipped with a clutch-member adapted to engage said first-named 20 clutch-member, means for elevating said shaft, a continuously rotating gear through which said shaft extends, and a friction clutch-member encompassed by said gear and driven thereby and having spline 25 connection with said shaft.

2. In a machine of the character set forth, the combination of a mold-carrier adapted to carry molds in an orbital path, a series of 30 molds mounted on said carrier, a nut mounted in alinement with each mold, a mandrel for each mold provided with a thread-equipped tip adapted to extend into the mold cavity and having a threaded shank engaging the corresponding nut and 35 having also a clutch-member at its lower end, a vertically movable shaft, a tiltable self-adjusting clutch-member mounted on the upper end of said shaft and adapted to engage said first-named clutch-member, 40 and continuously driven gear, mechanism equipped with a friction clutch adapted to drive said shaft.

3. In a machine of the character set forth, the combination of a mold-carrier adapted 45 to carry molds in an orbital path, a series of molds mounted on said carrier, a nut mounted in alinement with each mold, a mandrel for each mold provided with a thread-equipped tip adapted to extend into 50 the mold cavity and having a threaded shank engaging the corresponding nut and having also a clutch-member at its lower end, a vertical shaft disposed beneath the path of the mandrels, a self-aligning clutch-member mounted on the upper end of said shaft and positively driven by said shaft, continuously operating gear mechanism 55 equipped with a friction clutch and serving to actuate said shaft, and means for elevating said shaft.

4. In a machine of the character set forth, the combination of a mold equipped with 60 a nut, a threaded mandrel working through said nut and having a depending extremity 65 equipped with a clutch-member, a gear

equipped internally with a friction clutch, a shaft splined in said clutch, and means for elevating said shaft.

5. In a machine of the character set forth, the combination of a series of molds, a nut 70 associated with each mold, a threaded mandrel working through each of said nuts and having a depending extremity equipped with a clutch-member, a vertically movable shaft, continuously operating gear mechanism 75 equipped with a friction clutch for actuating said shaft and permitting stoppage thereof, and a pneumatic device disposed beneath said shaft and connected therewith by a bearing permitting free rotation of the shaft.

6. In a machine of the character set forth, the combination of a mold-carrier, a series 80 of molds mounted thereon, a nut associated with each mold, a tubular mandrel working through each nut and equipped at its lower end with a clutch-member, a vertically movable tubular shaft equipped at its upper end with a co-acting clutch-member, means for 85 rotating said shaft, said means being provided with a friction clutch permitting stoppage of the shaft, means for admitting air pressure through said shaft, and means for elevating said shaft.

7. In a machine of the character set forth, the combination of a mold-carrier, a series 90 of molds mounted thereon, a nut associated with each mold, a tubular mandrel working through each nut and equipped at its lower end with a clutch-member, a vertically movable tubular shaft equipped with a clutch-member having an air passage therethrough and adapted to engage said first-named clutch-member, means for rotating said 95 shaft, said means being equipped with a friction clutch to permit stoppage of the shaft, means for admitting air pressure through said shaft, and means for elevating 100 said shaft.

8. In a machine of the character set forth, 110 the combination of a mold-carrier, a series of molds mounted on said carrier, a nut associated with each mold, a tubular mandrel working through each nut and equipped at its lower end with a pinion and with a clutch-member, a pair of vertically movable shafts disposed at different stations, one of 115 said shafts being provided with an air passage, clutch-members mounted on the upper ends of said shafts, means for rotating said 120 shafts in opposite directions, said means including friction clutches permitting stoppage of the shafts, means for elevating said shafts, means for admitting air through said tubular shaft, and an auxiliary device comprising a rack adapted to engage the mandrel pinions and start the mandrels downwardly.

9. In means of the character set forth the combination of a mold equipped with a nut, 125

- a tubular mandrel working through said nut and equipped at its lower end with a clutch-member, a vertically movable clutch-member adapted to be raised into engagement with said first-named clutch-member, means for admitting air through said second-named clutch-member to the interior of the mandrel, and means for effecting rotation of said second-named clutch-member.
- 10 10. In means of the character set forth the combination of a mold, an associated nut, a tubular mandrel working through said nut and equipped at its lower end with a clutch-member, a vertically movable clutch-member equipped with a spring-held centering pin, and means for effecting rotation of said second-named clutch-member.
- 5
11. In means of the character set forth the combination of a mold, an associated nut, a tubular mandrel working through said nut and equipped at its lower end with a clutch-member, a vertically movable clutch-member equipped with a spring-held centering pin, and means for effecting rotation of said second-named clutch-member.

WARREN E. GLASPEY.
